[57] CLAIM

The ornamental design for a drill guide, as shown and described.

DESCRIPTION

FIG. 1 is a side elevational view of a drill guide, showing our new design;

FIG. 2 is a top plan view thereof;

FIG. 3 is a bottom plan view thereof;

FIG. 4 is a front elevational view thereof; and,

FIG. 5 is a rear elevational view thereof.

The broken line showing in FIGS. 1 through 5 are for illustrative purposes only and forms no part of the claimed design.
